UNITED STATES PATENT OFFICE.

MATTHIAS BROCK, DECEASED, LATE OF BOSTON, MASSACHUSETTS, BY EDWARD L. BROCK, ADMINISTRATOR, OF BEVERLY, MASSACHUSETTS, ASSIGNOR TO UNITED SHOE MACHINERY CORPORATION, OF PATERSON, NEW JERSEY, A CORPORATION OF NEW JERSEY.

LASTING MACHINE.

1,417,493.

Specification of Letters Patent. Patented May 30, 1922.

Application filed February 24, 1919. Serial No. 278,914.

To all whom it may concern:

Be it known that MATTHIAS BROCK, deceased, late of Boston, in the county of Suffolk and State of Massachusetts, invented 5 certain Improvements in Lasting Machines, of which the following description, in connection with the accompanying drawings, is a specification, like reference characters on the drawings indicating like parts in the several figures.

This invention relates to lasting machines, and is herein shown as embodied in a construction designed for use in machines of the general type illustrated in United States 15 Letters Patent No. 1,018,477, granted on Feb. 27, 1912, upon an application of Matthias Brock, numerous features of the construction herein shown having been further illustrated and described in Letters 20 Patent No. 1,373,482 granted upon an application of Matthias Brock on April 5, 1921. It is to be understood however, that in its broader aspects the invention is not limited to machines of the type shown in said patents 25 but is of general applicability to various types of construction.

A feature of the invention consists in improved means for applying clamping pressure on a shoe to assist in the lasting of the 30 shoe, the construction shown comprising a heel band and novel means for closing the band on the shoe constructed to operate with increased mechanical advantage as the pressure on the shoe increases. In machines of 35 the type illustrated in the prior patents above mentioned, the opposite ends of the heel band are connected to members which are moved lengthwise of the shoe and during their lengthwise movement are operated 40 upon by wedging mechanism which forces them laterally toward the sides of the shoe. As embodied, for example, in mechanism of this type, the invention in its illustrative embodiment provides wedging devices different 45 portions of the operative faces of which are inclined at different angles to the direction of the lengthwise movement of the members, the portions of said faces which are operative in the final application of the pressure being 50 more nearly parallel to said direction of

movement than the portions which are operative initially to swing the members toward the shoe. This construction affords provision for a comparatively quick initial closing movement of the band followed by a 55 slower movement with increased mechanical advantage in the final application of pressure to the shoe. In the illustrative embodiment of the invention the wedge faces are formed on the band closing members 60 through the provision of curved slots in the members, the wedge faces thus having a convex contour with the portions which are operative in the final application of the pressure to the shoe extending more 65 nearly lengthwise of the shoe than the other portions.

A further feature of the invention consists in novel means for relieving clamping pressure on a shoe, the construction shown comprising positive means for operating upon band closing members to force them laterally away from the shoe during their retracting movement lengthwise of the shoe. Insurance is thus afforded that the band shall be 70 fully open to receive another shoe, irrespective of any friction that there may be between the closing members and their supports. In the illustrative construction lateral movements of the band closing members both toward and from the shoe are effected by pin and slot connections between said members and a relatively fixed portion of the structure, the slots being curved as hereinbefore 75 explained for the purpose of increasing the effectiveness of the band closing means.

Another feature of the invention consists in novel means for applying clamping pressure locally on the lateral periphery of a shoe, the machine shown having a novel construction and arrangement of presser members for operating upon the heel band at the sides and rear corners of the heel end portion of the shoe to insure that the counter and the other upper materials shall be conformed 90 closely to the lateral surface of the last. In the construction shown the presser members are operated yieldingly through toggle mechanism and pressure equalizing connections as the band is closed on the shoe. 95 100

Still another feature of the invention consists in novel means for rendering power driven mechanism effective to operate upon a shoe, including provision for utilizing the 5 momentum of a driven part to perform a substantial portion of the work required in operating upon the shoe in each cycle of operations of the machine. In the construction herein shown, wherein the mechanism 10 for "jacking" the shoe is operated through a single revolution of an operating member, provision is afforded for connecting said member to a constantly driven fly wheel of such proportions as to perform a substantial portion of the work required by reason 15 of its own momentum. Advantageously in the construction shown the fly wheel is driven by an electric motor which is mounted on the frame of the machine, the use 20 of a fly wheel such as above described in connection with an individual motor drive rendering it feasible to use a motor of comparatively small horsepower, thus economizing in expense for the motor and also for the 25 electric current. As a further provision for rendering the driving mechanism effective, the construction shown includes a belt tightener which is connected to the mechanism 30 which actuates the clutch for connecting the fly wheel to the jacking means in such manner as to cause the belt to be tightened at the time when the work is performed, thus preventing the belt from slipping and rendering the power of the motor 35 fully effective in addition to the momentum of the fly wheel to insure the completion of the work on the shoe without any material decrease in the speed of rotation of the fly wheel. While this feature of the invention 40 is illustrated as applied to the work of "jacking" the shoe, whereby the shoe is clamped in a heel band preparatory to the operation of heel lasting wipers, it will be understood that in its broader aspects the invention is 45 not limited with respect to the character of the operation performed on the shoe.

The above and other features of the invention, including also a novel construction of work support, novel means for adjusting the limit of lateral movement of the heel 50 lasting mechanism for different styles of shoes, and various details of construction and combinations of parts will now be described with reference to the accompanying drawings and pointed out in the claims.

In the drawings,

Figure 1 is a view in front elevation of a machine in which the invention is embodied;

Fig. 2 is a view also in front elevation and on an enlarged scale of the heel lasting mechanism shown in Fig. 1;

Fig. 3 is a plan view of the heel lasting mechanism, with portions of the structure broken away to reveal parts that lie beneath;

Fig. 4 is a view in perspective of the mech-

anism for closing and applying pressure to the heel band;

Fig. 5 is a plan view of one of the band closing slide bars and the means for imparting lateral movement thereto;

Fig. 6 is a view in end elevation and partly in vertical section showing the driving means and portions of the mechanism connected therewith for jacking the shoe, and

Fig. 7 is a plan view showing a portion 75 of the mechanism for adjusting the lateral swing of the heel lasting carriage.

The machine herein shown comprises in its organization toe lasting means, heel lasting means, and means comprising a last pin 80 2 and a toe rest 4 for positioning the shoe for the toe and heel lasting operations. Since the present invention is not particularly concerned with the character of the toe lasting means, it will suffice to state that this 85 means comprises wipers 6 which are closed inward over the margin of the shoe bottom by the operation of a hand lever 8, the wipers and their operating parts being supported upon a vertically movable plunger 10 which is operated by a treadle 12 to cause the wipers to effect the "upwipe" prior to their overwiping operation. For a more complete understanding of the construction of the toe lasting mechanism reference may be 90 made to the patents above referred to.

The heel lasting mechanism is mounted upon a supporting carriage 14 which is arranged to be swung adjustably for right and left shoes about a vertical pivot 16, the carriage at its rear end having rolls which travel on a curved track 18. The swinging movement of the carriage is limited by stops 20 which are mounted equidistantly from the longitudinal median line of the machine 105 upon a right and left screw-threaded rod 22. Turning movement of this rod, effected by mechanism which will be hereinafter described, serves to adjust the stops 20 toward and from each other to determine the limits 110 of movement of the heel lasting mechanism properly in accordance with the "swing" of the last in different styles of shoes, the respective stops determining the proper positions of the mechanism for the right and 115 left shoes of each style.

As usual in machines of the illustrative type, the heel lasting mechanism is carried by a supporting head 23 which is mounted by means of rolls 24 upon the carriage 14 for 120 manual forward movement from an initial retracted position to bring it into position to operate upon the shoe, where it is retained by means of a catch 25 which engages a fixed lug on the carriage 14, the catch remaining 125 in holding position until it is lifted by mechanism including a cross bar 26 operated during the unjacking of the shoe after the lasting operation has been completed. The heel support, including the last pin 2, is 130

mounted on the head 23 and is movable thereon against the tension of a spring (not shown) to position the shoe in the correct relation to the heel lasting mechanism after 5 the head has been moved forward and locked by the catch 25, the heel support comprising for this purpose a block 28 slidably mounted in the head 23 and provided with teeth 30 in engagement with a pinion 32 also mounted 10 on the head, this pinion being operatively connected to a hand wheel 34 by which the heel support may be moved backwardly to carry the shoe into the heel band. In connection with the hand wheel 34 there is provided 15 locking mechanism 36 for retaining the heel support and the shoe in adjusted position, and the machine is also provided with means including a lever 38 for automatically releasing the locking mechanism to permit 20 relative separating movement of the shoe and the heel band after the lasting operation has been completed. For a more detailed illustration and description of these parts reference may be made to a prior Patent No. 25 1,404,188 granted upon an application of Matthias Brock on Jan. 24, 1922.

In the construction shown the heel support is particularly adapted for use in lasting long legged boots, and for this purpose comprises 30 a substantially U-shaped member 40 which may be integral with the block 28, as shown, the front arm 42 of the U-shaped member having a socket to receive and permit upward and downward movement of a 35 spindle 44 which carries the last pin 2. In order to impart to the shoe the upward movement characteristic of machines of the illustrative type as the shoe is moved backwardly into the heel band, to position the 40 plane of the heel seat in the desired relation to the wipers, the arm 42 of the heel support is provided with a lengthwise bore to receive a rod 46 which engages the head of an adjustable screw 48 in the lower end of the 45 spindle 44, the lower end of the rod 46 being operatively engaged by one arm of a lever 50, the other arm of which is connected yielding 50ly to a rod 52 slidable lengthwise in the U-shaped member 40 and having at its upper 55 end a roll 54 for engagement with an inclined face on a cam member 56 which is secured on the head 23. It will be evident that as the heel support is moved rearwardly by the hand wheel 34 the rod 52 is depressed 60 by the action of the cam 56 and through the connections above described serves to impart yieldingly upward movement to the last pin 2 and the shoe. This construction also is similar to what is shown and described in 65 said prior Patent No. 1,404,188. As distinguished from the construction shown in said patent, the present invention provides a construction designed to facilitate the lasting of long legged boots the uppers of which 65 are curved inwardly at the back near the top

of the boot to approximate the shape of the wearer's leg. A difficulty has been encountered heretofore in lasting such boots due to the fact that engagement of the upper rear part of the leg of the boot with the heel support extending within it has tended to tip the entire upper of the boot relatively to the last in such manner as to lift the heel end portion of the upper and thus displace it and prevent perfect lasting. In order to remedy 70 this difficulty the front arm 42 of the U-shaped member 40 is so constructed as to provide upper and lower portions which extend in angular relation to each other, the lower portion of the arm being offset toward 75 the left (Fig. 1) in such manner as to avoid interference with the inwardly curved top portion at the back of the boot.

The heel wipers 58 (Fig. 3) are mounted on carrier plates 59 connected by means of 80 links 60 to a cross bar 62 connected at a point intermediate between its ends to a rod 64 which is movable forwardly against the tension of a spring 66 and is operatively connected to a hand lever 68 whereby operative 85 forward movement is imparted to the wipers. In order to cause the wipers to close inward laterally over the shoe as they are advanced, the wiper carriers 59 are provided with slots 70 within which are positioned rolls 72 90 supported independently of the carrier plates. As the carrier plates and the wipers are advanced, the rolls 72 cause the carrier plates to swing in such manner as to impart the lateral closing movement to the wipers. The rolls 72 are mounted on pins 74 which extend into slots 76 in a cover plate 78 secured on the top of the lasting mechanism, and are connected by means of links 80 to a rod 82 encircled at its outer end by a 95 spring 84 which bears oppositely upon the bearing through which the rod slides and upon a collar 86 secured to the rod. The spring 84 thus tends to move the rod 82 rearwardly in such manner as to hold the 100 roll supporting pins 74 substantially at the rear ends of the slots 76, provision being afforded, however, for adjustment of the normal position of the rolls by means of a stop screw 88 mounted in the end of the rod 105 82 for engagement with a stop 90. As the wipers are advanced by the operation of the lever 68, the spring 84 tends to hold the rod 82 and the links 80 in position to restrain the rolls 72 from bodily movement. In case, 110 however, unusual resistance to the bodily advancing movement of the wipers is encountered, as for example where the upper stock is unusually heavy and tends to "bunch" at the rear end of the heel seat, the 115 outwardly directed pressure of the wiper carriers on the rolls causes them to move lengthwise of the guide slots 76 while pulling the links 80 and the rod 82 forwardly against the tension of the spring 84, thus 120 125 130

accelerating the lateral closing movement of the wipers while permitting them to close over the end of the heel seat with a comparatively slow rate of movement. This construction affords insurance against cutting or marring the margin of the upper at the rear of the heel seat when unusual conditions such as above described are encountered.

Below the wipers 58 is mounted the heel band, the specific construction of which is not material to the purposes of the present invention, this band in the construction shown comprising a flexible shoe engaging portion 92 molded substantially to the contour of the shoe and mounted upon a support comprising a series of pivotally connected links 94 which may be termed for convenience a chain. The heel band is supported at its rear end upon a yoke 96 which is adjustably mounted on the head 23 for movement in directions laterally of the shoe to position the heel band properly for right and left shoes, the adjusting movement of the yoke being effected by means of a hand wheel 98. At its front end the heel band is supported on levers 100 which are fulcrumed on the front ends of slide bars 102 supported on the yoke 96 and connected by means of links 104 to a cross bar 106 which is pivotally mounted between its ends on a rod 108 movable lengthwise in the head. The rod 108 carries at its outer end a block 110 connected by a spring 112 to an operating lever 114 on a rock shaft 116, this shaft having fast thereon a depending lever 118 which is operatively engaged by a plunger rod 120 to which movement is imparted by a bell crank 122 mounted on the carriage 14. The bell crank 122 carries a roll 124 which underlies a cap 126 on a rod 128 vertically slideable on the frame of the machine and operated by mechanism to be hereinafter described. It will be understood that when the cap 126 is moved downwardly the bell crank 122 operates the plunger rod 120 and through the levers 118 and 114 applies tension to the spring 112 to move the rod 108 and the connected slide bars 102 forwardly to clamp the heel band against the shoe. The levers 100 on the ends of the slide bars are connected at their outer ends to springs 130 which tend to swing them in a direction to draw the ends of the heel band laterally away from the shoe and yield to permit the band to be closed inward against the shoe through the action of the slide bars 102 and also yield in response to any continued movement of the slide bars after the band has been clamped firmly against the shoe.

Each of the slide bars 102 is provided with a curved slot 132 within which is mounted a roll 134 pivotally supported on the yoke 96, this slot and roll connection causing the slide bars to swing inward toward the sides of the shoe as they are ad-

vanced to force the heel band laterally against the shoe. The curved slots 132 provide convex wedge faces 133 on the slide bars, different portions of which are disposed in such relation to the direction of lengthwise movement of the bars as to cause a comparatively rapid initial swinging movement of the bars to close the band against the shoe, followed by a comparatively slow lateral movement of the bars with increased mechanical advantage in the final application of pressure to the ends of the band. This operation will be readily understood by reference to Fig. 5 wherein it will be seen that the portion of the wedge face 133 upon which the roll 134 is first effective is inclined at a greater angle to the direction of lengthwise movement of the bar than that portion of the face upon which the roll is effective during the final portion of the movement.

It will be understood that when the cap 126 is raised, after the lasting operations have been completed, and the catch 25 is lifted to release the heel lasting mechanism, the spring 112 becomes effective by its reaction against the operating connections to impart an initial impulse to the lasting mechanism to force it away from the shoe toward its normal idle position. The simultaneous release of the rod 108 and the connected parts from the tension of the spring 112 permits the springs 130 to act to swing the levers 100 outwardly from the shoe and also to move the slide bars 102 rearwardly to their initial position. During this rearward movement of the bars 102 the rolls 134 by their engagement with the inclined faces at the outer sides of the slots 132 insure that the bars shall also be swung outwardly in such manner as properly to open the heel band for the reception of another shoe.

In order to apply additional pressure to the heel band at the sides and the inwardly curved rear corners of the band, the machine is provided with side presser blocks 136 and with corner presser blocks 138, these blocks being arranged to engage the chain 94 at the sides and the rear corners of the band respectively and having inner faces which are concavely curved in substantially the same shape as the band. The blocks 136 are pivotally supported on rods 140 and the blocks 138 are similarly supported on rods 142, these several rods being slidingly mounted in the supporting head. The connections between the blocks and the rods comprise slots in the blocks within which reduced flattened portions of the rods extend to their pivotal points, the rods presenting curved shoulders 144 which are arranged to engage the outer faces of the blocks in any position which the blocks may assume relatively to the rods, this construction serving to relieve the pivotal connec-

tions between the blocks and the rods from any substantial strain. At their outer ends the rods 140 and 142 on each side of the machine are engaged by an equalizing lever 5 146 pivotally mounted on the front end of a lever 148 which is pivoted at 150 to the supporting head. The levers 148 at their rear ends are pivotally connected to links 152 which are pivoted in turn to an equalizing lever 154 provided with a depending pin 156 engaging in a slot 158 in an operating lever 160 pivotally mounted at 162 on a bracket 164 on the supporting head. Extending loosely through the lever 160 is a 10 rod 166 encircled by a spring 168 which bears at one end on the lever and at its other end on a tension adjusting nut 170 on the end of the rod. The rod 166 is pivotally connected at its front end to a bar 172 which 15 is pivoted in turn to a crank arm 174 on the rock-shaft 116. It will be evident that when the shaft 116 is rocked by depression of the cap 126 in the manner hereinbefore described to close the heel band upon the shoe, 20 the spring 166 is simultaneously compressed against the lever 160 and operates through this lever and the connections comprising the equalizing lever 154, the toggle links 152 and the side levers 148 to force the rods 30 140 and 142 inwardly toward the shoe and thus to cause the blocks 136 and 138 to bear with increased pressure against the sides and rear corners of the heel band, the levers 146 serving to equalize the pressure as between 35 the sides and the corners of the band. When the ends of the band are released in the manner hereinbefore described, the tension of the spring 168 is also relaxed to permit the pressure blocks 136 and 138 to be without 40 drawn to their initial positions coincidently with the opening of the band.

The operation usually termed the "jacking" of the shoe includes in the construction herein shown not only the application of the 45 heel band to the shoe in the manner above described but also an elevation of the toe rest 4 to raise the toe end of the shoe into proper relation to the toe wipers and to tip the shoe backwardly into the heel band as 50 the band is closed against the sides of the shoe, although the term as used herein is not to be understood as limited to a combination of these different operations or restricted with respect to the precise character of 55 the operations performed on the shoe. For elevating the toe portion of the shoe the toe rest is mounted upon a vertically movable slide 176 (Fig. 6) which carries a roll 178 engaging the periphery of a cam 180 60 mounted on a cam shaft 182. Mounted also on the shaft 182 is a cam 184 which engages a roll 186 on a lever 188 connected by a link 190 to the lower end of the rod 128 on which the cap 126 is mounted. The shaft 182 carries also a ratchet wheel 192 provided in the

construction shown with six teeth engaged by a pawl 194 on a pawl carrier 196 which is mounted to turn about the shaft 182. It will be understood that when the ratchet wheel 192 is advanced one sixth of a revolution by the operation of the pawl 194, one of the three projections of the cam 180 is effective to raise the slide 176 and the toe rest and one of the three projections of the cam 184 is effective to operate the lever 188 75 in such manner as to depress the cap 126 and close the heel band on the shoe, the machine then coming to rest with the parts in this position to permit the operation of the toe and heel wipers, and that when the ratchet wheel 192 is advanced another sixth of a revolution the cams are rendered effective to release the toe rest and the cap 126 and thus to permit the parts to return to their normal starting positions. In the construction herein shown the pawl 194 is operated by power, the pawl carrier 196 for this purpose being connected by means of a link 198 to a crank arm 200 fast on a normally idle shaft 202. Keyed on this shaft 202 and slidable lengthwise thereof is a clutch sleeve 204 (Fig. 1) which is provided with a toothed clutch face and is normally urged by a spring toward a similar toothed clutch face on the hub of a driving element or pulley 206 which normally rotates idly on the shaft 202. A rib 208 on the periphery of the clutch sleeve 204 is so disposed as to act as a cam against which normally bears an arm 210 extending rigidly from a pivotally mounted hub 212 to hold the clutch sleeve 90 disengaged from the pulley. The hub 212 has also extending rigidly therefrom an arm 214 which is operatively engaged by a spring pressed arm 216 to maintain the arm 210 in 100 clutch releasing position. Extending upwardly from the hub 212 is a crank arm 218 pivotally connected to which is a rod 220 arranged to be operated by pressure of the operator's knee against a member 222. When 110 the operator presses against the member 222 the arm 210 is withdrawn from the cam 208 to permit the clutch sleeve 204 to be operatively connected to the pulley 206. The member 222 is then immediately released, 115 and the arm 216 operating upon the arm 214 immediately returns the rear arm 210 into position to engage the cam 208 and to disengage the clutch sleeve from the pulley 120 at the end of a single revolution in which the cams are operated to elevate the toe rest and to close the heel band on the shoe. After the lasting operation on the shoe has been completed the member 222 is again operated to render the clutch effective to impart a 125 single revolution to the shaft 202 and the crank arm 200, whereby the cams are turned a sufficient distance to permit the toe rest to return by gravity to its initial position and to cause the heel band to be released 130

from closing pressure and the catch 25 to be elevated by the member 26 in order to release the heel lasting mechanism and permit it to be retracted from the shoe.

5 It will be evident that when the clutch is tripped to cause the power to be applied for rotating the cams 180 and 184 to elevate the toe rest and to close the heel band about the shoe, the resistance to movement of the cams 10 rapidly increases up to the point where the cams cease to impart further movement to the operating connections, at which time the parts of the clutch are again disconnected, substantially at the end of a single revolution of the pulley 206. In order to increase the effectiveness of the driving means and avoid any undesirable results incident to the sudden increase of resistance, the pulley 206 is constructed to serve as a fly wheel, being 15 sufficiently heavy to cause a large proportion of the work required to be done in the single revolution of the clutch to be performed by the momentum of this element. While this construction has important advantages irrespective of the character of the source of power, it is of particular advantage where the power is derived from an individual electric motor, such as 224, which in the construction shown is mounted on a bracket 226 20 on the frame and is connected to the fly-wheel pulley 206 by a belt 228. This construction and arrangement of the parts, including provision for utilizing momentum of the member 206 to do a considerable portion of the work required each time that the clutch is tripped, permits the use of a motor of comparatively small horsepower, thus economizing both in the cost of the motor and in the expense for the electric current, since it is possible to use a motor much smaller than would be required if the motor alone were depended upon to overcome the sudden heavy resistance incident to the jacking of the shoe. In order further to increase 25 the effectiveness of the driving means, the machine is provided with a belt tightening pulley 230 carried by a swinging arm 232 and connected by means of a spring 234 to a rod 236 which at its lower end is pivotally connected to a lever arm 238 rigid with the hub 212 of the clutch actuating means. When the clutch is tripped the pulley 230 is thus swung downward in such manner as to increase the tension of the driving belt 228. 30 This affords additional insurance against any slipping of the belt when the clutch is tripped and renders the force of the motor fully effective in addition to the momentum of the pulley to assist in performing the required work, while avoiding strain on the parts and excessive wear of the bearings in the comparatively long periods when the motor and the pulley are running idly.

Reference has been made hereinbefore to 35 the use of the shaft 22 for adjusting the stops

20 to determine the different limits of lateral swinging movement of the heel carriage 14 for different styles of shoes. The mechanism provided for turning the shaft 22 in the construction shown comprises a hand lever 240 which is mounted on the frame at the same end of the machine as the toe lasting mechanism and within convenient reach of the operator as he stands in his normal working position. The hand lever 240 is 70 connected by gearing 242 to a shaft 244 which extends downwardly at the rear of the machine and is connected at its lower end by means of gearing 246 to the shaft 22. This construction is a substantial improvement over prior constructions in respect to convenience in effecting the required adjustment of the limiting stops.

Having described the invention, what I claim as new and desire to secure by Letters 85 Patent of the United States is:

1. In a machine of the class described, the combination with shoe end clamping means, of mechanism for operating said clamping means to cause it to press upon a shoe comprising a member adjacent to the shoe end having a wedge face formed to operate with increasing mechanical advantage as the pressure on the shoe increases.

2. In a machine of the class described, the combination with shoe clamping means, of operating means comprising a member movable lengthwise of a shoe to cause said clamping means to press upon the shoe, and wedge mechanism for forcing said member toward 95 the shoe during its movement lengthwise of the shoe including a wedge face different portions of which are relatively arranged to render the mechanism effective with increased mechanical advantage in the latter 100 portion of the operative movement of said member.

3. In a machine of the class described, the combination with shoe clamping means arranged to engage a shoe on its opposite sides, 110 of mechanism for operating said clamping means to cause it to press upon the shoe, said mechanism comprising members movable lengthwise of the shoe and means for wedging them toward the sides of the shoe 115 during said lengthwise movement, said wedging means being constructed to cause the members to operate with increased mechanical advantage as the pressure on the shoe increases.

4. In a machine of the class described, the combination with an end embracing band, of mechanism for operating said band to cause it to press upon a shoe comprising wedging devices for the opposite sides of the band 125 having wedge faces formed to operate with increasing mechanical advantage as the pressure on the shoe increases.

5. In a machine of the class described, the combination with an end embracing band, 130

of members connected to the opposite sides of said band for closing it on a shoe, and wedging means having wedge faces formed to effect movement of said members toward the sides of the shoe with increased mechanical advantage as resistance to the closing of the band increases.

6. In a machine of the class described, the combination with an end embracing band, of means for closing said band on a shoe, said closing means comprising members having wedge faces formed to impart a comparatively quick initial closing movement to the band followed by a slower movement with increased mechanical advantage as the resistance increases.

7. In a machine of the class described, the combination with an end embracing band, of means for closing said band on a shoe, said closing means comprising wedge members having wedge faces different portions of which are differently inclined to render said mechanism effective with increased mechanical advantage in the final portion of the closing movement of the band.

8. In a machine of the class described, the combination with an end embracing band, of members connected respectively to the opposite side portions of the band to close it on a shoe, and wedge mechanism for rendering said members effective to close the band against the sides of the shoe, said wedge mechanism having wedge faces formed to operate with increased mechanical advantage in the final application of pressure to the band.

9. In mechanism of the class described, the combination with an end embracing band, of devices adjacent to the opposite side portions of the band and movable lengthwise of the shoe to close the band on the shoe, and wedging means to force said devices inwardly toward the sides of the shoe during their movement lengthwise of the shoe, said wedging means including wedge faces different portions of which are differently inclined to the direction of movement of the devices lengthwise of the shoe to increase the effectiveness of the devices in the final application of band closing pressure.

10. In a machine of the class described, the combination with clamping means arranged to engage a shoe on its opposite sides, of mechanism for operating said clamping means to cause it to press upon the shoe including members movable lengthwise of the shoe and means for wedging them toward the sides of the shoe during said lengthwise movement, said wedging means including wedge faces convexly curvy with the portions of said faces that are operative in the final application of pressure disposed more nearly lengthwise of the shoe than other portions of the faces.

11. In a machine of the class described,

the combination with an end embracing band, of band closing members connected to the opposite side portions of the band and movable lengthwise of a shoe to close the band on the shoe, said members having wedge faces convexly curved on a general incline to the direction of said movement of the members while approaching in their rearward extent a parallel relation to said direction of movement, and means for engaging said faces to cause the members to move inwardly toward the sides of the shoe during their movement lengthwise of the shoe.

12. In a machine of the class described, the combination with an end embracing band, of band closing members connected to the opposite side portions of the band and movable lengthwise of a shoe to close the band on the shoe, and means for wedging said members toward the sides of the shoe during said lengthwise movement, said wedging means including wedge faces convexly curved with the portions of said faces that are operative in the final application of pressure disposed more nearly lengthwise of the shoe than other portions of said faces.

13. In a machine of the class described, the combination with an end embracing band, of bars connected to the opposite side portions of said band and movable lengthwise to close the band on a shoe, said bars extending in substantially parallel relation to the lengthwise dimension of the shoe and having slots therein curved on a general incline to the direction of their lengthwise movement, and abutment members in said slots for causing the bars to move laterally toward the sides of the shoe during their lengthwise movement.

14. In a machine of the class described, the combination with an end embracing band, of band closing members adjacent to the opposite side portions of the band and movable lengthwise of a shoe to close the band on the shoe, said members having slots therein inclined to said direction of movement of the members, and abutments in said slots to cause the members to move inwardly toward the sides of the shoe as they move lengthwise of the shoe, the portions of said slots in which the abutments are located in the latter portion of the band closing movement of the members extending more nearly lengthwise of the shoe than the other portions of the slots.

15. In a machine of the class described, the combination with an end embracing band, of members connected to the opposite side portions of the band for closing it on a shoe, said members extending in substantially parallel relation to the lengthwise dimension of the shoe and having slots therein inclined laterally of the shoe, means

- for moving said members lengthwise of the shoe, and abutments in said slots to cause the members to move inwardly toward the sides of the shoe during their movement 5 lengthwise of the shoe.
16. In a machine of the class described, the combination with clamping means arranged to engage the opposite sides of a shoe, of an operating member movable in 10 one direction lengthwise of the shoe for causing said clamping means to press upon the shoe and in the opposite direction for releasing the pressure, and positive means acting substantially midway between the opposite ends of said member to force it toward and from the sides of the shoe in the respective movements of the member lengthwise of the shoe.
17. In a machine of the class described, 20 the combination with an end embracing band, of members for applying closing pressure to the opposite side portions of said band, means at the outer ends of said members for moving them in one direction lengthwise of the shoe to apply said pressure and then in the opposite direction to release the pressure, and means for wedging said members laterally toward and away from the sides of the shoe during their respective 25 movements lengthwise of the shoe.
18. In a machine of the class described, the combination with an end embracing band, of members for applying closing pressure to the opposite side portions of said 30 band, means connected to the outer ends of said members for moving them in one direction lengthwise of the shoe to apply said pressure and then in the opposite direction to release the pressure, said members having 35 slots between their opposite ends inclined laterally of the shoe, and abutments in said slots to cause the members to move laterally toward and from the sides of the shoe in their respective movements lengthwise of the shoe.
19. In a machine of the class described, 40 the combination with clamping means for engaging the side of a shoe, of a member movable lengthwise of the shoe to cause said clamping means to press upon the shoe and then in the reverse direction to release the pressure, and wedge mechanism constructed and arranged to swing said member about an axis substantially at its outer end to force 45 it laterally outward from the side of the shoe during said reverse movement of the member.
20. In a machine of the class described, 50 the combination with clamping means for engaging the side of a shoe, of a member movable lengthwise of the shoe to cause said clamping means to press upon the shoe and then in the reverse direction to release the pressure, means connected to the outer end 55 of said member to operate it, and positive
- means acting between the opposite ends of said member to force it laterally outward from the side of the shoe during its reverse movement.
21. In a machine of the class described, 70 the combination with clamping means for engaging the side of a shoe, of a member extending throughout its length at one side of the longitudinal median line of the shoe and movable lengthwise of the shoe to cause 75 said clamping means to press upon the shoe and then in the reverse direction to release the pressure, and wedge mechanism including a slot in said member and an abutment in said slot for moving the member laterally toward and from the side of the shoe during its movements lengthwise of the shoe.
22. In a machine of the class described, 80 the combination with shoe clamping means, of mechanism for operating said clamping means to cause it to press upon a shoe, means for rendering said mechanism effective with increased mechanical advantage as the clamping pressure increases, and additional mechanism arranged to operate through said 85 clamping means to increase the clamping pressure.
23. In a machine of the class described, 90 the combination with clamping means arranged to engage a shoe at its opposite sides, 95 of mechanism for operating said clamping means to apply pressure to the shoe, said mechanism comprising levers mounted to cause their front ends to swing toward and from the sides of the shoe, toggle mechanism between the rear ends of the levers for forcing them apart, and means operative independently of resistance of the shoe for operating said toggle mechanism to clamp the shoe.
24. In a machine of the class described, 100 the combination with clamping means arranged to engage a shoe at its opposite sides, 105 of mechanism for operating said clamping means to apply pressure to the shoe, said mechanism comprising levers mounted to cause their front ends to swing toward and from the sides of the shoe, toggle links connected to the rear ends of said levers, an operating member connected to said links, 110 and yieldable means operative independently of resistance of the shoe to impart movement to said operating member for clamping the shoe.
25. In a machine of the class described, 115 the combination with shoe positioning means, of presser members arranged to apply pressure respectively at the sides and the corners of the end portion of a shoe on its lateral periphery, and operating means 120 including pressure equalizing mechanism to cause said members to bear upon the sides and the corners of the shoe with substantially equal pressures.
26. In a machine of the class described, 125

the combination with shoe positioning means, of presser members arranged to apply pressure respectively at the sides and the corners of the end portion of a shoe on its lateral periphery, operating means comprising levers for forcing said members toward the shoe, and pressure equalizing rockers mounted on said levers for operating said members.

10 27. In a machine of the class described, the combination with shoe positioning means, of relatively movable presser members arranged to apply pressure respectively at the sides and the corners of the end portion of a shoe on its lateral periphery, and operating means comprising levers the inner ends of which are operatively related to said members and toggle mechanism for moving the outer ends of said levers apart for forcing said members toward the shoe.

28. In a machine of the class described, the combination with shoe positioning means, of a plurality of presser devices slidably mounted at one side of the longitudinal median line of the shoe for applying pressure against the lateral periphery of the shoe, and operating means supported independently of said devices and arranged to move them toward the shoe.

30 29. In a machine of the class described, the combination with shoe positioning means, of a plurality of presser members arranged to operate at one side of the longitudinal median line of the shoe for applying pressure against the lateral periphery of the shoe, operating means comprising a lever supported independently of said members and a pressure equalizing connection between said lever and the different members, 40 and mechanism for imparting operative movement to said lever.

30 30. In a machine of the class described, the combination with shoe positioning means, of a presser member arranged to apply pressure on the lateral periphery of the shoe, an operating member upon which said presser member is pivoted to swing about an axis substantially perpendicular to the plane of the shoe bottom, said operating member being mounted in a guideway to slide toward and from the shoe, and means for moving said operating member toward the shoe.

31. In a machine of the class described, 55 the combination with shoe positioning means, of a presser member arranged to apply pressure on the lateral periphery of the shoe, and an operating member upon which said presser member is pivoted, said operating member having a shouldered portion arranged to bear against the presser member to relieve the strain on the pivotal connection between said members.

32. In a machine of the class described,

the combination with shoe positioning means, of a presser member arranged to apply pressure on the lateral periphery of the shoe, and an operating member pivotally connected to said presser member, said presser member having a slot within which 70 said operating member extends and the operating member having a shouldered portion to bear against the presser member outside of said slot to relieve the strain on the pivotal connection between said members. 75

33. In a machine of the class described, the combination with shoe positioning means, of a presser member arranged to apply pressure on the lateral periphery of the shoe, a rod upon which said presser member 80 is supported, said rod being mounted to slide toward and from the shoe, and means for applying pressure to the outer end of said rod to force the presser member toward the shoe. 85

34. In a machine of the class described, the combination with shoe positioning means, of presser members arranged to apply pressure respectively in different locations on the lateral periphery of the shoe, 90 90 slideable rods for imparting operative movement to said members, and means including a pressure equalizing device arranged to bear on the outer ends of said rods to force the presser members toward the shoe. 95

35. In a machine of the class described, the combination with shoe positioning means, of presser members arranged to apply pressure respectively in different locations on the lateral periphery of the shoe, 100 100 slideable rods for imparting operative movement to said members, mechanism including an operating lever for moving said rods lengthwise toward the shoe, and a pressure equalizing rocker pivotally mounted on said 105 lever to cause the presser members to apply substantially equal pressures to the shoe.

36. In a machine of the class described, the combination with shoe positioning means, of presser members arranged to apply pressure respectively in different locations lengthwise of the shoe at its opposite sides, operating means comprising levers supported independently of said members for forcing the members toward the shoe, 115 115 and pressure equalizing rockers mounted on said levers for operating said members.

37. In a machine of the class described, the combination with an end embracing band, of operating means connected to the 120 opposite side portions of the band and movable lengthwise of a shoe for closing the band on the shoe, wedge mechanism for forcing said operating means inwardly toward the sides of the shoe as it moves 125 lengthwise of the shoe, said mechanism being constructed to operate with increased mechanical advantage as the pressure on

- the shoe increases, and additional means movable inwardly toward the shoe for forcing the band against the shoe.
38. In a machine of the class described, 5 the combination with a shoe end embracing band and means for closing said band on the shoe, of additional means for applying pressure to the band comprising members arranged respectively to press against the 10 band in fixed locations at the sides and the corners of the end portion of the shoe, and means for imparting pressure applying movement to said members simultaneously.
39. In a machine of the class described, 15 the combination with a shoe end embracing band and means for closing said band on the shoe, of additional means for applying pressure to the band comprising members arranged to press against the band at the sides 20 and the corners of the end portion of the shoe, and mechanism connected yieldingly to the band closing means for imparting pressure applying movement to said members.
- 25 40. In a machine of the class described, the combination with a shoe end embracing band, of means connected to the ends of said band for closing it on the shoe, members arranged to apply pressure on the opposite 30 side portions of the band, a pivotally mounted operating member, and independent connections between said operating member and said closing means and presser members.
41. In a machine of the class described, 35 the combination with an end embracing band, of means for operating said band to apply pressure to a shoe, said operating means comprising levers mounted to permit their front ends to swing toward and from 40 the sides of the shoe, toggle mechanism between the rear ends of the levers for forcing said ends apart, and means movable toward the end of the shoe to operate said toggle mechanism.
- 45 42. In mechanism of the class described, the combination with a shoe end embracing band and means for closing said band on a shoe, of presser members arranged to bear upon the opposite side portions of the band, 50 levers for forcing said members toward the shoe, and toggle mechanism between the outer ends of said levers for operating them.
43. In a machine of the class described, 55 the combination with a shoe end embracing band, of presser devices slidably mounted for bodily movement toward and from the band independently of each other, and operating mechanism including pressure equalizing means for causing said devices to operate upon the band with substantially equal pressures.
44. In a machine of the class described, 60 the combination with a shoe end embracing band, of a pair of presser blocks arranged to bear on said band at each side of the shoe,
- slidably mounted rods on which said blocks are supported, and operating mechanism including pressure equalizing means arranged to bear upon the outer ends of said rods to apply pressure to the band. 70
45. In a machine of the class described, the combination with a shoe end embracing band, of means connected to the ends of said band for closing it on a shoe, means arranged to apply pressure to the band in fixed 75 locations opposite to the sides and the corners of the end portion of the shoe, and mechanism connected to said closing means and pressure applying means for operating them in unison. 80
46. In a machine of the class described, the combination with a shoe end embracing band, of slide bars connected to the opposite ends of said band and movable lengthwise and laterally to close the band about a shoe, 85 presser blocks arranged to apply pressure to the band at the sides and the corners of the end portion of the shoe, operating means, and separate connections between said operating means and the slide bars and presser blocks. 90
47. In a machine of the class described, the combination with toe lasting mechanism at one end of the machine, of heel lasting mechanism at the other end of the machine 95 mounted to swing laterally into different positions for operating respectively on right and left shoes, means at the heel end of the machine for limiting the swinging movements of the heel lasting mechanism, and mechanism for adjusting said limiting means, said adjusting mechanism extending into position to be operated at that end of the machine where the toe lasting mechanism is located. 100
48. In a machine of the class described, the combination with toe lasting mechanism, of heel lasting mechanism mounted to swing laterally into different positions for operating respectively on right and left shoes, 110 stops for limiting the swinging movements of the heel lasting mechanism, a rotatable shaft for adjusting said stops for different styles of shoes, an adjusting member adjacent to the toe lasting mechanism, and gearing connecting said member with said rotatable shaft for adjusting the stops. 115
49. In a lasting machine, the combination with a shoe support and shoe end clamping means and operating mechanism for jacking a shoe in said clamping means constructed to come automatically to a stop after the jacking operation to permit the lasting of the shoe to be completed manually, of power driving means comprising an individual motor of insufficient power to perform the jacking operation unaided, and a driving element operated continuously by said motor and arranged to be connected momentarily to said operating mechanism for the jack- 120
- 125
- 130

ing operation, said driving element comprising a fly wheel of sufficient mass to perform a substantial portion of the jacking operation by its momentum and arranged to be speeded up by the motor in each interval when said operating mechanism is at rest.

50. In a lasting machine, the combination with means for jacking a shoe, of a constantly rotating driving element having sufficient momentum to perform a substantial portion of the work required in said jacking operation, an electric motor connected to said driving element and having insufficient power to perform said jacking operation unaided, and mechanism for connecting said element to the jacking means and for disconnecting it therefrom after the jacking operation has been performed.

51. In a lasting machine, the combination with means for jacking a shoe, of a constantly rotating driving element having sufficient momentum to perform a substantial portion of the work required in said jacking operation, an electric motor having insufficient power to perform said jacking operation unaided, a belt connecting said motor to the driving element, a clutch for connecting said element to the jacking means and for disconnecting it therefrom after the jacking operation has been performed, means for actuating said clutch, and belt tightening means arranged to be operated by said clutch actuating means for tightening the belt when the power is applied to the machine.

52. In a machine of the class described, the combination with operating means for performing an operation on a shoe, of a constantly rotating driving element having sufficient momentum to perform a substantial portion of the work required in said operation on the shoe, an electric motor connected to said driving element, said motor having insufficient power to perform said operation on the shoe unaided, and means for connecting said driving element to said operating means and for disconnecting it therefrom after the operation on the shoe has been performed.

53. In a machine of the class described, the combination with operating means for performing an operation on a shoe, of a constantly rotating driving element having sufficient momentum to perform a substantial portion of the work required in said operation on the shoe, an electric motor having insufficient power to perform said operation on the shoe unaided, a belt connecting said motor to said driving element, a clutch arranged to connect said driving element to said operating means and to disconnect it therefrom after the operation on the shoe

has been performed, clutch actuating means, and means arranged to be operated by said clutch actuating means for tightening said belt when the power is applied to the machine.

54. In a machine of the class described, the combination with operating means for performing an operation on a shoe, of a constantly rotating driving element, a belt for rotating said element, a clutch for connecting said element to the operating means, clutch actuating means, and means operated by said clutch actuating means for tightening the belt when the power is applied to the machine.

55. In a machine for operating on shoes, the combination with operating mechanism constructed to come automatically to a stop at the end of the cycle of operations on a shoe, of power driving means comprising an individual electric motor of insufficient power to perform the cycle of operations unaided, and a driving element operated continuously by said motor and clutch controlled for connection with said operating mechanism at each cycle of operations, said driving element having sufficient mass to perform a substantial portion of the cycle of operations by its momentum and arranged to be speeded up by the motor at the end of each cycle to supplement the action of the motor in the succeeding cycle.

56. In a machine of the class described, the combination with lasting mechanism, of means for supporting a long legged boot in position to be operated upon by said mechanism, said supporting means comprising an arm arranged to extend lengthwise into the leg of the boot, said arm being laterally offset in that portion which is opposite to the top of the boot leg to prevent interference with the upper of a boot the top portion of which is curved inwardly at the back of the leg.

57. In a machine of the class described, the combination with lasting mechanism, of means for supporting a long legged boot in position to be operated upon by said mechanism, said supporting means comprising a substantially U-shaped member one arm of which is adapted to extend lengthwise through the boot leg, different portions of said arm being disposed in angular relation to each other to prevent interference with the upper of a boot the top portion of which is curved inwardly at the back of the leg.

In testimony whereof I have signed my name to this specification.

EDWARD L. BROCK,
Administrator of the estate of Matthias
Brock, deceased.
